Primary Examiner — Eric Goodman*Assistant Examiner* — Bao-Yen Nguyen(74) *Attorney, Agent, or Firm* — Charles N. Quinn; Fox Rothschild LLP(57) **CLAIM**

I claim the ornamental design for a stroke limiter bracket, as shown and described.

DESCRIPTION

FIG. 1 is an isometric view of a stroke limiter bracket, showing my new design;

FIG. 2 is another isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top view thereof; and,

FIG. 8 is a bottom view thereof.

1 Claim, 3 Drawing Sheets(56)
